UNITED STATES PATENT OFFICE.

NELLE M. THOMPSON AND EDWARD F. O'LEARY, OF PUEBLO, COLORADO.

COPY-HOLDER.

1,306,788.

Specification of Letters Patent. Patented June 17, 1919.

Application filed December 20, 1915. Serial No. 67,898.

To all whom it may concern:

Be it known that we, NELLE M. THOMPSON and EDWARD F. O'LEARY, citizens of the United States, and residents of Pueblo, in the county of Pueblo and State of Colorado, have invented certain new and useful Improvements in Copy-Holders, of which the following is a full, clear, and exact description.

Our invention relates to copy holders and particularly to copy holders designed and intended for holding stenotype notes. The principal object of our invention is the provision of a simple, compact machine adapted to receive the notes in the condition in which they are taken from the stenotype machine, that is to say with the last part of the dictation on the outside of the roll, to reroll the notes by power driven means so as to expose the beginning of the dictation, and then to gradually wind the notes back on the first spool, this last winding being automatically accomplished in a step-by-step manner through mechanism actuated by the typewriter on which the notes are being transcribed.

A further object of our invention is to so design the machine and select the reciprocating or rocking part of the typewriter from which the power to actuate our machine is derived that the speed of travel imparted to the notes shall be as nearly identical with the speed at which the notes are read as may be.

A still further object is to provide a device of this character which is of such construction that the same may be readily attached to and operated by any of the well known makes of typewriters now on the market; and to so construct it that it will be capable of being placed on either side of the typewriter with which it is to be used—thus accommodating it to the preference of the individual user or to the requirements of the construction of any particular make of machine.

Other objects and advantages of our invention will later appear in this specification.

In the three sheets of drawings accompanying this application and forming a part hereof—

Figure 1 is a perspective view of a complete stenotype note holder embodying our

invention as attached to a typewriter, only sufficient parts of the latter being illustrated to show the manner of connection of our device thereto and the means by which it is actuated;

Fig. 2 is an enlarged detail in side elevation of one of the upper reels or spool holders, a portion of the ratchet housing appearing in vertical section to show the ratchet pawl;

Fig. 3 is a similar view of the lower spool holder on the opposite side of the machine;

Fig. 4 is a still larger detail in end view of the ratchet housing and ratchet as viewed from the inner side, the housing again appearing in section;

Fig. 5 is an enlarged perspective of a portion of the frame showing a spool holder receiving socket;

Fig. 6 is a plan view of the machine, the upper spool and holders, portions of the frame and of the stenotype notes being broken away to disclose the rear parts;

Fig. 7, a section taken on the line 7—7, Fig. 2; and

Fig. 8, a section on the line 8—8, Fig. 6, looking in the direction of the arrow drawn across said line.

As previously stated our machine is so designed as to be capable of use on either side of the typewriter, the assemblage illustrated adapting it for use on the right hand side of the typewriting machine. In the general description, for convenience, the parts will be designated as the right hand or left hand parts as they appear in the drawing without reference for the time being to whether or not when the machine is reversed they will still occupy the same relative positions and the description is to be read with this explanation in mind.

Referring to the drawings, 10 indicates the frame of the device which may be conveniently composed as shown of a pair of triangular side members joined by spanner rods. Each side member is provided with two downwardly slotted sockets 11 (see Fig. 5) each of which is adapted at its bottom to provide a bearing for one of the spool holders. These spool holders are all similar in certain features and all differ slightly in others; each comprises a disk 12 adapted to abut against the end of a spool and act as a guide for the paper reeled thereon and each

having projecting therefrom a pin 14 which is adapted to lock a spool against rotation relative to the disk.

The spool holder for the upper left hand side, shown in Fig. 2, comprises a screw-headed stud 15 provided with a reduced screw-threaded shank 16 which ends in a shoulder against which the disk 12 is adapted to abut and against which the disk is firmly held by an interiorly threaded cap 17 screwed on the shank 16. This cap also forms an axle adapted to enter a centrally disposed socket in the spools and thus to support the same. Non-rotatably mounted on the stud 15 outside of the disk 12 there is a pair of sleeves 18 joined into an integral structure by a collar 19. The spool shaped structure thus formed is adapted to straddle a side member of the frame and retain the spool holder against lateral movement, the collar 19 falling into the bottom of the slot 11 and revolving therein. A ratchet wheel 20 is non-rotatably mounted on the stud 15 and the ratchet housing 22 is revolvably mounted on the stud 15. The ratchet housing carries pivotally mounted therein the pawl 23 which is adapted to engage the teeth of the ratchet and is normally forced into such engagement by the spring 24. This spring 24 is carried by a stud 25 which is slidably mounted in a circumferential slot 26 in the housing, the friction between the stud and the casing being sufficient to retain the stud in any position in which it may be manually adjusted. The free end of the spring 24 is bent outward at 27 and passes out through another circumferential slot in the casing for a purpose later to be described. The casing 22 is provided with a radially projecting lug 29 which forms a means for connecting thereto a link 30 to be later described.

The lower left hand spool holder is like the upper left hand one just described except that it carries no ratchet or ratchet casing and therefore is shorter.

The lower right hand spool holder is shown in Fig. 3. This holder is preferably constructed with a square stud ending on the outer side in a knurled knob 32 and on the inner side in a round threaded shank 33 on which a cap 34 is adapted to be screwed. In this form the disk 12 and the spool shaped retaining member 18 are also squared to fit on the stud 31, the disk being free to slide to the right of the cap 34 but normally held thereagainst by the coiled spring 35. This disk 12 also carries rigidly attached thereto the gear 36.

The upper right hand spool holder is like the lower except that in this case the gear 36 is omitted.

The link 30, which is preferably round, is received in a similarly shaped socket in the member 37 in which it is held in longi-

tudinally and angularly adjustable position by the set-screw 38. The member 37 is pivotally connected at its lower end to a U-shaped member which is adapted to pass under the side member 39 of a typewriter and which U-shaped member is provided on its inner end with a socket containing member 40 adapted to be passed over the end of a spacer bar of a typewriter and to be secured thereto by a set-screw 41. The horizontal portion of the U-shaped member is composed of coöperating slotted sections 42, 43, which, with the adjusting bolts 44, provide means for adjusting the U-shaped member to accommodate it to use with various makes of typewriters—the distance which it is to span varying in different machines.

The portion of the machine heretofore described is that which serves to actuate the notes in step-by-step manner as they are transcribed and this part of the machine is capable of use alone without the note winding mechanism to be later described, the rewinding of the notes in such case being accomplished manually. We, however, prefer to add the mechanism now to be explained, which mechanism serves to wind the notes on the lower spool and thus to expose that portion of the notes first taken. The lower members of the frame 10 are each provided with a projection 46 which contains a rearwardly and downwardly extending slot adapted to receive and journal the reversible shaft 47. This shaft carries at one side a gear 48 adapted to mesh with the gear 36 and in the middle a gear 49 adapted to mesh with a gear 50 on any suitable motive device. That shown is a spring motor 51 mounted on a shaft 52 journaled in the frame and provided with squared ends with which a crank or the like 53 may coöperate for winding and with the ratchet mechanism 54 for preventing unwinding. The motor is also provided with a brake 55 for controlling its speed, the brake being normally held in operative position in engagement with the motor casing by the spring 56 and being adapted to be released by pressure exerted against the spring.

Operation.

Assuming that the notes have just been taken off the stenotype machine, the upper right hand disk 12 is forced to the right against the action of its spring and the spool containing the notes is inserted; after which, the spring 35 being released, the spool is firmly grasped between the disks, the caps 16 and 33 and the pins 14 entering suitable sockets provided for them in the spool. The free end 27 of the spring 24 is then pressed to slide the spring to the right in Fig. 4 and the inner end of the spring 24 engages the shoulder 57 on the pawl 23 raising it and holding it out of engagement with the

ratchet, thus rendering for the time being this portion of the machine inoperative. Then the free end of the stenotype notes is attached to the lower spool and the brake 55 5 depressed to allow the spring motor to re-roll the notes on the lower spool. After this rewinding has taken place the shaft 47 is moved longitudinally to disengage the gears 36 and 48 and the pawl 23 is returned to the 10 position shown in Fig. 4. The machine is now ready for the transcribing of the notes. Each downward movement of the spacer bar will turn, through the chain of mechanism described, the casing 22 through a sufficient 15 angle to allow the pawl 23 to fall over one tooth of the ratchet, the friction of the spools in their mountings being sufficient to prevent a backward turn thereof during this movement. Then when the spacer bar rises 20 under the action of the spring of the typewriter the casing 22 will, through the engagement of the pawl 23 with its ratchet, cause the upper spool to turn a sufficient amount to wind one line of the notes on the 25 upper spool. Inasmuch as stenotype notes average substantially one line to a word and since the note holding mechanism is, through the means selected for its actuation, only moved at the end of each word we have 30 provided a means whereby the travel of the notes will be substantially always equal to the speed at which they are read and transcribed. If the winding be too slow, however, the notes can be readily advanced by 35 turning the upper spool forward; or, if too fast, they can be wound back by merely freeing the pawl 23 and turning the knurled knob 32.

If it is desired to change our machine from 40 one standing at the right hand side of the typewriter as shown to one for the opposite side of the machine, no new or different parts are needed. In such a case the spool holding members are all reversed to the opposite side 45 of the machine from which they now occupy and the shaft 47 turned end for end, the fact of the gear 49 being in the middle of the shaft permitting this. The pawl and ratchet mechanism must now also be reversed on the 50 stud 15 in order that the travel of the upper reel shall be in the proper direction. This may readily be accomplished by removing the cap 17 and all the parts which it retains on the stud and reassembling the spool holder 55 with the housing 22 and its contents in reversed position. This same result could also be obtained without the necessity of disassembling the spool holder by providing the housing 22 with two ratchets and pawls, one 60 of the latter being always retained in inoperative position by its spring 24. The adjustment provided by the link 30 and the sleeve member 37 enables the connection between the typewriter and the note holder to 65 be adjusted to accommodate the latter to use

with varying machines and on varying arrangements of typewriter desks and also readily permits of the disconnection of the machines if the typewriter is to be closed up in a folding desk. 70

If the typewriter and copy holder stand free upon a desk or table it is desirable to provide a separable connecting means 60 for holding them in their proper relative position. This may be any design of clamp carried by either the typewriter or copy holder frame and detachably secured to the frame of the other machine. 75

If desired as an aid in keeping the place on the notes pointers 61 carried by the side 80 members of the frame and extending over the notes may be provided.

While we have described our invention in detail in the foregoing specification in the best embodiment of it with which we are now 85 familiar, we do not desire to be considered as limited to these details. It will be obvious, for instance, that other rocking parts of the typewriter may be selected as actuating means for our copy holder and that these and 90 other changes may be made without departing from our invention the scope of which we have defined in the appended claims.

In the appended claims we have employed the term "reel" to indicate the combination 95 of two spool holders and the associated spool or an equivalent therefor and the claims should be read in view of this explanation.

Having thus described our invention, what we claim and desire to secure by Letters Pat- 100 ent is:—

1. In a device of the class described, a symmetrical note holder frame, a typewriter, a pair of reversible reels carried by said frame, a ratchet-movement reversibly se- 105 cured to one of said reels, and a link connection of adjustable length connecting the spacer bar of said typewriter to the said ratchet.

2. In apparatus of the character described, 110 the combination of a rotary reel, means for the rotary support of a spool, a device for winding a strip from a spool supported by said means, upon the reel, mechanism for converting an intermittent motion of an 115 actuating element into a step-by-step rotation of the spool-supporting means to rewind the strip upon the spool, and adjustable appliances controlling the operation of said mechanism and said device to permit either 120 one to perform its respective function unrestrained by the other.

3. In apparatus of the character described, the combination of a rotary reel, means for the rotary support of a spool, a motor, a 125 gearing for rotating the reel by the action of the motor, including a member which is adjustable to break the operative relation between the motor and the reel to permit of independent rotation of the latter, and mech- 130

4
anism for converting an intermittent motion of an actuating element into a step-by-step rotation of the spool-supporting means including a movement which is adjustable to break 5 the operative relation between the actuating element and the spool-supporting means, to permit of independent rotation of the latter.

4. The combination with the spacing-bar of a typewriter, of a rotary spool-support, a 10 rotary reel, a device for winding a strip from a spool on the support onto the reel, mechanism to convert each reciprocation of the spacing bar into a corresponding rotary movement of the spool-support to rewind the 15 strip upon the spool, and adjustable appliances controlling the operation of the device

and the mechanism to permit either one to perform its respective function unrestrained by the other.

5. The combination with the spacing-bar 20 of a typewriter, of a rotary spool-support, a rotary reel adapted to receive a strip unwound from a spool on the support, and mechanism acting directly upon the spool-support to convert each reciprocation of the 25 spacing bar into a corresponding rotary movement thereof.

In testimony whereof we have hereunto affixed our signatures.

NELLE M. THOMPSON.
EDWARD F. O'LEARY.
